A. L. MOBLEY

NURSING BOTTLE

Filed Oct. 21, 1921

Inventor
A. L. Mobley.

By *John Ralph J.* Attorney

UNITED STATES PATENT OFFICE.

ALONZO L. MOBLEY, OF SOQUEL, CALIFORNIA.

NURSING BOTTLE.

Application filed October 21, 1921. Serial No. 509,402.

To all whom it may concern:

Be it known that I, ALONZO L. MOBLEY, a citizen of the United States, residing at Soquel, in the county of Santa Cruz and 5 State of California, have invented certain new and useful Improvements in a Nursing Bottle; and I do hereby declare the following to be a full, clear, and exact description of the invention, such as will enable others 10 skilled in the art to which it appertains to make and use the same.

Nursing bottles are generally made of glass and are formed with angular portions within and without and as a consequence 15 they are fragile, difficult to clean and frequently injure the infant.

The present invention provides an indestructible bottle which may be easily cleaned and is not liable to injure the infant because 20 it is free from corners and angular portions.

The invention also provides a nursing bottle which is readily accessible for cleaning, which permits of the use of either the 25 breast nipple or the ordinary nipple as desired.

Other objects and advantages will be apparent and suggest themselves as the nature of the invention is understood.

30 While the drawing illustrates an embodiment of the invention it is to be understood that in adapting the same to meet different conditions and requirements various changes in the form, proportion and minor details of 35 construction may be resorted to without departing from the nature of the invention.

Referring to the accompanying drawing forming a part of the specification,

Figure 1 is an elevation of a nursing bottle 40 embodying the invention showing the same adapted for receiving the usual small nipple.

Figure 2 is a sectional detail, the lower portion of the bottle being omitted, and

45 Figure 3 is a detail view showing the bottle adapted for use in connection with the breast nipple.

Corresponding and like parts are referred to in the following description and designated in the several views of the drawing by like reference characters.

50 A nursing bottle constructed in accordance with my invention is practically indestructible and free from corners or angular 55 projecting parts and is of sectional formation to admit of either type of nipple being

used therewith as indicated most clearly in Figures 1 and 3 of the accompanying drawing. While any material that will withstand hard usage and heat and cold may be employed, it is preferred to construct the bottle of aluminum which is light and not affected by liquid contents and capable of withstanding hard usage and sudden changes in temperature. The bottle is of 60 sectional formation and comprises a body portion 1 and a neck portion 2. The parts 1 and 2 are preferably connected by means of a screw thread joint which has inner and outer abutting shoulders to prevent leakage. 65 The juncture of the side walls with the bottom is rounding as indicated at 3 and 4 thereby obviating inner angular corners and outer angular projections with the result that the bottle may be readily cleaned 70 and is not liable to injure the infant. The body is provided at its mouth with an outer beam 5 for reinforcing and strengthening 75 purposes and also to provide for positive engagement of the breast nipple 6 as indicated in Figure 3. The body 1 is threaded for a short distance upon its interior as indicated at 7 and makes screw thread engagement with the neck portion 2. The inner threaded portion 7 is located adjacent the 80 mouth of the body 1 and the latter is stiffened upon its inner wall as indicated at 8 to further reinforce and strengthen the bottle as well as to provide an inner shoulder 9 to abut the threaded end of the part 2. The 85 inner lower portion of the stiffened part 8 vanishes into the inner wall of the body 1 to prevent the formation of any projecting part which would tend to collect matter and render it difficult to clean the bottle. 90

The neck portion 2 is made tapering and has an outer bead 10 at its smaller end to provide a finish to reinforce and strengthen the mouth of the part 2 and to provide positive means for attachment of the ordinary 100 small nipple 11 as indicated in Figure 1. The coupling end of the part 2 is externally threaded as indicated at 12 to make screw thread engagement with the part 7 of the body 1. The threaded portion 12 is reduced 105 leaving an outer shoulder 13 which is adapted to abut the extremity of the body 1. When the part 2 is coupled to the part 1 the outer shoulder 13 is in contact with the outer end of the part 1 and the inner shoulder 9 of the part 1 is in contact with the extremity of the part 2. These abutting 110

joints at the ends of the threaded portion insure a tight joint and prevent leakage.

When it is required to use the ordinary small nipple 11 the part 2 is coupled to the 5 part 1 but when it is desired to use the breast nipple 6 the part 2 is disconnected from the part 1 and the latter has the breast nipple fitted thereto as indicated in Figure 3. The sectional formation of the bottle 10 admits of the same being readily cleaned as will be readily understood. The outer surfaces of the parts 1 and 2 adjacent the joints are milled, chased or otherwise roughened as indicated most clearly in Figure 1 to 15 enable a firm grip to be obtained thereon when screwing or unscrewing the parts.

Having thus described the invention, what I claim is:—

A nursing bottle comprising body and 20 neck portions, the body portion having the juncture of its side and bottom walls curved both internally and externally, internal screw threads adjacent the open end of the body portion, a shoulder within the body at

the inner end of said screw threads, external 25 screw threads at the lower end of the neck portion, a shoulder on the neck portion at the inner end of the screw threads and adapted to abut the outer edge of the body when the neck portion is threaded to the body portion, the inner edge of the neck portion adapted to abut the inner shoulder in the body of the bottle when the neck is threaded to the body, the neck and body 30 portions of the bottle each having a nipple 35 securing bead at their outer end, the outer end of the neck portion being of much less diameter than the body portion whereby either a breast nipple or an ordinary nipple 40 may be used, and the neck and body portions being serrated adjacent their point of connection.

In testimony whereof I affix my signature in presence of two witnesses.

ALONZO L. MOBLEY.
